CLAIM

The ornamental design for an animal training device, as shown and described.

DESCRIPTION

FIG. 1 is a perspective view of an animal training device showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view of the animal training device of FIG. 1 shown with environment, the broken lines forming no part of the claimed design.
